US00D551529S

(12) **United States Design Patent** (10) **Patent No.:** **US D551,529 S**
Youngren et al. (45) **Date of Patent:** **** Sep. 25, 2007**

(54) **HAMMER**

(75) Inventors: **Robert H. Youngren**, Rockford, IL (US); **Bruce V. Johnson**, Sterling, IL (US)

(73) Assignee: **Estwing Manufacturing Company**, Rockford, IL (US)

(**) Term: **14 Years**

(21) Appl. No.: **29/255,433**

(22) Filed: **Mar. 8, 2006**

Related U.S. Application Data

(63) Continuation-in-part of application No. 11/211,380, filed on Aug. 25, 2005, which is a continuation of application No. 10/658,693, filed on Sep. 9, 2003, now Pat. No. 6,976,406, which is a continuation of application No. 10/214,237, filed on Aug. 7, 2002, now Pat. No. 6,647,829.

(57) **CLAIM**

The ornamental design for a hammer, as shown and described.

DESCRIPTION

FIG. 1 is a rear right side perspective view of a hammer showing my new design;

FIG. 2 is a front right side perspective view of the hammer;

FIG. 3 is a front left side perspective view of the hammer;

FIG. 4 is a rear left side perspective view of the hammer;

FIG. 5 is a front elevation view of the hammer;

FIG. 6 is a rear elevation view of the hammer;

FIG. 7 is a right side elevation view of the hammer;

FIG. 8 is a left side elevation view of the hammer

FIG. 9 is a top plan view of the hammer; and,

FIG. 10 is a bottom plan view of the hammer. The broken line portions of the disclosure are for illustrative purposes only and form no part of the claimed design.

1 Claim, 8 Drawing Sheets
